UNITED STATES PATENT OFFICE.

GEORGE E. STARKWEATHER, OF LOS ANGELES, CALIFORNIA, ASSIGNOR OF ONE-FOURTH TO THOMAS A. HOLLAND AND ONE-FOURTH TO BRYAN CHAMBERS, BOTH OF LOS ANGELES, CALIFORNIA.

HEATER.

Application filed May 16, 1927. Serial No. 191,772.

This invention relates to a water heater of the instantaneous type, and has for its object to provide, in a manner as hereinafter set forth, a water heater of such class including a thermostatic controlled heating element, and further with the water heater so constructed and arranged to obviate the necessity of a storage tank for hot water, as well as a water heater including means to provide for the back circulation of the heat of the water when not discharging hot water and when discharging hot water providing for the incoming cool water to circulate around the thermostatic element to avoid over-heating.

A further object of the invention is to provide, in a manner as hereinafter set forth, an instantaneous water heater including a thermostatic controlled heating element and further with the water heater constructed and arranged to overcome piston sticking and expense of repacking with respect to a thermostatic element which controls the water heating element or burner.

Further objects of the invention are to provide, in a manner as hereinafter set forth, a water heater of the instantaneous type which is comparatively simple in its construction and arrangement, strong, durable, compact, thoroughly efficient in its use, readily assembled and comparatively inexpensive to set up.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a vertical sectional view of a water heater in accordance with this invention.

Figure 2 is a sectional plan thereof.

Figure 3 is a section on line 3—3 Figure 1.

Referring to the drawings in detail a water heater, in accordance with this invention includes a pair of concentrically arranged, spaced, vertically disposed cylin-

drical shells 1, 2 of appropriate height and connected together at their upper ends by a flat annulus 3 which is integral with the shells 1 and 2. The outer shell, which is indicated at 1, depends below the lower end of the inner shell 2 and said shells 1 and 2, in connection with the annulus 3, form an air chamber 4 of annular contour. The shells 1, 2 are mounted upon the top of a stepped annular base 5 formed with openings 6 providing air intake openings for the chamber 4. The steps of the base 5 are indicated at 7, 8 the former arranged above the latter and the riser between the steps 7 and 8 is indicated at 9. The shell 1 is seated on the step 8 and abuts against the riser 9. The shell 2 is seated on the inner portion of the step 7 and abuts against the heating element or burner which is formed integral with the base 5.

The heating or burner element consists of an annular casting, referred to generally by the reference character 10 and which is arranged within, integral with and depends above and below the top of the base 5. The shell 2 abuts against that portion of the casting 10 which extends above the top of the base 5. The casting 10 is formed with an outer annular chamber 11, a circular central chamber 12 and a series of radially disposed tubular portions 13 which establish communication between the chambers 11 and 12. Each tubular portion 13 is formed with a set of jet openings 14. The outer openings of each set of openings are positioned at the ends of the tubular portion 13. The casting 10 at the axis of its top and axis of its bottom is formed with openings 16, 17 respectively having threaded walls and arranged in alignment. The top of the casting has an integral upstanding peripherally threaded collar 18 aligning with the walls of the opening 16. The bottom wall of the annular chamber 11 is formed with an opening 19 and is further formed with a depending tubular flaring extension 20 to which is secured an air intake element 21 having connected therewith a gas supply line 22 which opens into the intake element 21 for supplying gas to the extension 20. The line 22 is disposed below the base 5 and is provided with a controlling valve 23. The line 22 rearwardly of the valve or cut-off 23 has mounted therein and extended therefrom a

thermostatic controlled cut-off 24 and com-

municating with the line 22 rearwardly of the cut-off 24 and extending into the heating chamber 25, formed by the shell 2, is a pilot light or burner 26.

5 Mounted upon the shells or casings 1, 2, as well as being secured therewith in any suitable manner, is a closure 27 for the top of the chamber 25. The closure 27 is formed with a depending annular flange 28 which 10 abuts against the inner face of the shell or casing 2. The closure 27 is of a diameter to extend beyond and surround the upper part of the shell or casing 1. Centrally of the closure 27, it is formed with an opening 15 28 and also with an upstanding annular flange 29 which forms a continuation of the opening 28. Connected to the flange 29 is a conducting pipe 30. The opening 28 provides an outlet for the chamber 25 and the 20 pipe 30 conducts off the fumes from such chamber.

Seated upon the top of the casing 10 and threadably engaging with the collar 18, is a vertically disposed sleeve 31 which gradually increases in diameter from its lower to its upper end and has the inner face thereof, at its upper end provided with interior threads 32. Arranged within the chamber 25 and threadably engaging, at its 25 lower end with the threads 32 of the sleeve 31, is a vertically disposed sleeve 33 of uniform diameter throughout and of greater length than the sleeve 31. The lower end of the sleeve 32 extends into the upper end of the sleeve 31. Connected to the upper end of the sleeve 33 is an elbow 34, having its upper arm 35 gradually decreasing in diameter from its inner towards its outer end and which has connected therewith, as well 30 as opening thereinto, a cold water supply pipe 36, which extends through the shells 1 and 2 has its outer end provided with a T-coupling 37. Attached to the T-coupling 37 and depending therefrom is a valve controlled cold water supply line 38. The sleeves 31 and 33 form a cool water receiving chamber 39 having arranged therein a thermostatic controlling element, to be presently referred to, for the cut-off 24.

35 Arranged within the heating chamber 25 is a set of communicating, concentrically arranged water heating coils. The set includes inner, intermediate and outer coils 40, 41 and 42. The lower end of the coil 40 is connected with the sleeve 31, as at 43 and communicates with the chamber 33. The upper end of the coil 40 is connected to the upper end of the coil 41 as at 44. The lower end of the coil 41, is connected to the lower end 40 of the coil 42 as at 45. The set of coils extend from the elbow 34 to a point below the top of the sleeve 31. The coils are arranged in enveloping position with respect to the sleeve 33 and with respect to approximately 45 the upper half of the sleeve 31. The upper

end of the coil 42 is extended, as at 46 and passes through the shells 1 and 2 and opens into a hot water discharge line 47, provided intermediate its ends with a T-coupling 48, to which is connected a by-pass 49, provided with a check valve 50. The by-pass 49 is connected to the T-coupling 37.

The thermostatic element includes a vertically disposed tube 51 of expandible metallic material, such as copper and which is formed with a closure 52 for the upper end thereof. The lower end of the tube 51 is open. The periphery, at the lower terminal portion of the tube 51, is threaded, as at 53. The lower terminal portion of the tube 51 extends through the openings 16, 17 and has threaded engagement with the walls of said openings, as well as threaded engagement with interior threads 54 formed on the collar 18. The tube 51 is connected to the top and bottom of the casting 10. The tube 51 is of materially less diameter than the inner diameter of the sleeves 31, 33. Arranged within the tube 51 is a vertically disposed shifting rod 55, preferably constructed of porcelain extending from the closure 52 and depends below the bottom of the casting 10. The lower end of the rod 55 is pointed, as indicated at 56. The rod 55 is shifted on the contraction of the tube 51 and the function of said rod is to normally maintain the cut-off 24 in open position to provide for a supply of gas to the heating element or burner. The rod 55 coacts with a spring controlled pivoted lever arm 58, notched as at 59 for the reception of the pointed end 56 of the rod 55. The bottom of the casting 10 is formed with an apertured lug 60, to which is pivotally connected, as at 61, the inner end of the lever arm 58. The notch 59 is arranged in proximity to the pivot 61. The outer end of the lever arm 58 has a pin and slot connection with the stem of the cut-off 24, and connected to the outer end of the lever arm 58 is a controlling spring 62 which is anchored to the casting 10. The controlling spring 62 functions to shift the cut-off 24 to closure position to discontinue the supply of gas to the heating or burner element. The function of the rod 55 is to act on the lever arm 58, against the action of its controlling spring, for the purpose of maintaining the cut-off in open position and normal condition of operation with respect to the water heater. When the tube 51 is expanded, the spring 62 will elevate the lever arm 58, as the rod 55 can be shifted upwardly within the tube, but on a contraction of the tube 51, the rod 55 will be moved downwardly, acting on the lever arm 58 so as to move the cut-off 24 to open position and hold it in such position until the rod 55 can be released, on the expansion of the tube 51 so that the spring 62 can shift the cut-off to closure position.

The check valve 50 acts to close the bypass 49, to the supply pipe 36, when the hot water discharge line 47 is opened and the incoming cold water will be conducted into the chamber 39 and from there enter the inner coil 40. When the hot water discharge line 47 is closed, the check valve 50 is not seated and the heat of the hot water can be utilized to heat the water in the pipe 36 and 10 chamber 39 or in other words a back circulation is had for the heat of the water. The tube 51 has its upper end positioned a substantial distance below the upper end of the sleeve 33. The manner of setting up the cold 15 water receiving chamber with respect to the thermostatic element, avoids the over-heating thereof, due to the supply of cold water to such chamber and quickly causes the contraction of the tube 51 to provide for the 20 supply of gas for combustible purposes when the hot water is discharged.

It is thought the many advantages of a water heater, in accordance with this invention, can be readily understood, and although the preferred embodiment of the invention is as illustrated and described, yet it is to be understood that changes in the details of construction can be had which will fall within the scope of the invention as 25 claimed.

What I claim is:

1. A water heater comprising a heating chamber, a set of communicating, concentrically disposed coils arranged within said 30 chamber, a cold water receiving chamber arranged within the heating chamber, sur-

rounded by said coils and communicating in proximity to its lower end with the inner coil of the set, a valve controlled cold water supply line extending into the heating chamber and communicating with the receiving chamber at the top thereof, a hot water discharge line communicating with the outer coil of said set, a by-pass between said lines and provided with a check valve, a heating element arranged at the bottom of the heating chamber, and control means therefor including a thermostatic element arranged within said receiving chamber. 40 45

2. In a water heater, a casing providing a heating chamber, a hollow support for said casing, said support having a part thereof providing a burner extending into said chamber at the lower end thereof, water heating coils arranged within said chamber, a cold water receiving chamber of less height than and positioned within the heating chamber and surrounded by and communicating with said coils, said cold water receiving chamber having its lower end closed by 50 said burner, control means arranged below said support and within and extending from said cold water receiving chamber and including a thermostatic element, said means controlling the supply of fuel to said support for said burner, a cold water supply line opening into the top of said receiving chamber, and a hot water discharge line extended from said coils to said casing. 55 60 65

In testimony whereof, I affix my signature 70 hereto.

GEORGE E. STARKWEATHER.
